No. 884,937.

PATENTED APR. 14, 1908.

R. B. LAWRENCE.
FIRE DOOR FASTENER.
APPLICATION FILED AUG. 8, 1907.

UNITED STATES PATENT OFFICE

RUSSELL B. LAWRENCE, OF NEW YORK, N. Y.

FIRE-DOOR FASTENER.

No. 884,937.

Specification of Letters Patent. Patented April 14, 1908.

Application filed August 8, 1907. Serial No. 387,633.

To all whom it may concern:

Be it known that I, RUSSELL B. LAWRENCE, a citizen of the United States, and a resident of the city of New York, borough of 5 Queens, in the county of Queens and State of New York, have invented a new and Improved Fire-Door Fastener, of which the following is a full, clear, and exact description.

10 This invention relates to means for securing a fire door in locked position, so as to prevent a fire from spreading in the interior of a building. When doors of this character are subjected to excessive heat arising from a 15 fire, the doors warp and shrink transversely of their length, thereby forming an aperture between the edge of the door and its casing or its adjacent door section, and enabling the flames to spread by passing through said 20 aperture.

This invention has for its object, therefore, to provide means adapted to hold a fire door against warping or shrinking in width so as to prevent the fire from spreading beyond 25 said door.

Other objects relating to the specific construction and special arrangement of the several parts constituting my invention will be understood from the following description 30 and accompanying drawings, in which drawings like characters of reference indicate like parts throughout the views, and in which

Figure 1 is a perspective view of a double door provided with my invention; Fig. 2 is a 35 transverse sectional view of the meeting edges of the two sections of the door, taken on the line 2—2 of Fig. 3; Fig. 3 is an enlarged side elevation of a part of the device shown in Fig. 1; and Fig. 4 is a perspective 40 view of a keeper used in carrying out my invention.

As illustrated in the accompanying drawings, 1 and 2 represent the sections of a double door provided with hinges 3, the 45 plates of which extend in opposite directions and are fastened to a door section and casing 4 respectively. The free edge of one of the door sections is provided with an astragal 5 which overlaps the corresponding edge of the 50 opposite door section so as to cover the joint between said edges. A carrying bar 6 is mounted upon the free edge of one of the door sections, and is adapted to slide in

guideways 7 preferably attached to the astragal of the door. The carrying bar 6 is connected in any suitable manner with a latch 8 preferably by means of a loop 9 formed on the carrying bar which engages the free end 10 of said latch. A latch spindle 11 or other suitable device is connected with the latch 60 and adapted thereby to move the carrying bar 6 up and down in its guideway 7.

Mounted on the carrying bar 6 are latches 12 provided with apertures 13 adapted to engage keepers 14 secured to the opposite door 65 section 1, or to a door casing. The keepers 14 are provided with base plates 15 having apertures 16, by means of which and engaging screws the keepers are secured in their places. The keepers 14 are also provided 70 with open recesses 17 adapted to receive the latches 12 and hold the latches and the doors attached thereto against any outward movement. In addition to preventing any outward movement of the free end of the door 75 section, the latches 12 bear at their outer portion against the side of the keepers and prevent the door shrinking or warping transversely of its length, the hinges 3 at the same time holding the opposite edge of the door 80 against warping or shrinking in the same direction.

When the device is in use, the doors are opened by raising the carrying bar 6 by means of the latch 8 or otherwise, which 85 raises the latches 12 and releases the upper portion of the latches from engagement with the recesses 17 of the keepers. The doors are closed and locked by a reverse or downward movement of the carrying bar 6 after 90 the doors have been closed, thereby again bringing the upper portion of the latches 12 into engagement with the recesses 17 of the keepers.

Having thus described my invention, what 95 I claim as new and desire to secure by Letters Patent is:

1. The combination with a fire door, of an astragal, a carrying bar having a sliding engagement with said door, latches mounted on 100 said bar, and keepers comprising a base plate and an off-set recessed lip adapted to engage and hold said latches against a strain transversely of said door.
2. The combination with a fire door, of an 105 astragal, a carrying bar having a sliding en-

gagement with said door, a latch mounted on said door and adapted to operate said bar, and keepers comprising a base plate and an off-set recessed lip adapted to engage and hold said latch against a strain transversely of said door.

In testimony whereof I have signed my

name to this specification in the presence of two subscribing witnesses.

RUSSELL B. LAWRENCE.
